ZEBINA EASTMAN, OF CHICAGO, ILLINOIS.

Letters Patent No. 89,210, dated April 20, 1869.

IMPROVEMENT IN THE CONSTRUCTION OF STREET-RAILWAYS.

The Schedule referred to in these Letters Patent and making part of the same.

To all whom it may concern:

Be it known that I, ZEBINA EASTMAN, of Chicago, in the State of Illinois, at present residing abroad as the United States consul at Bristol, England, have invented a new and useful Improvement in Iron Rails for Cars Running in Streets of Cities, which invention was patented in the United States Patent Office, dated September 3, 1867, No. 68,421; and whereas, I have since discovered new and important improvements in the form and construction of the rails, to be used in conjunction with the said patent, and with the rails therein described, I do hereby declare the following to be a full, clear, and exact description of the nature, construction, and operation of the improvement I have made, reference being had to the accompanying drawings, which are made part of this specification, which are as follows:

Figure 1 is a plan view of a full size No. 1 rail, of the particular form and construction of my rail.

A is a vertical or transverse section of the same rail, showing its shape as seen from the end.

B is a top view, or the rail as seen in the street when laid in position.

B² is the same rail, with a change in the shape of the notches. References 1 1, (the white spaces,) are the raised parts between the notches, on the edges of the rails which are left flush, or full to the surface when the rail is rolled.

2 2 are the depressed parts, shaded, or notched between the raised parts 1, which by their form, present open places, in which the tires, or rims of the wheels will catch when coming out of the groove.

They also furnish a foothold on which the shoe or hoof of the horse may catch, and not slip, when he happens to strike the surface of the rail.

These notches are made in different forms, as seen in B and B², so as to be better adapted to the use that may be required of them.

Figure 2 is a view of the same rail on a scale of one-fourth to one inch, with an accompanying perforated flange, or supporting piece, and a chair

A is a sectional or end view of the same.

B B² are side views of the parts of the rail above the supporting flange or stringer, which is laid within the paving.

In A, c is the wedged-shaped flange or supporting

stringer of the rail, rolled with the upper part of the rail, and made part of it when practicable, or it may be made of cast-iron, as seen in this plan, and if cast, it will be made with a slot, or opening at the top to receive the flange of the wrought rail, which is held down in its place by the bolt d.

e is a bolt holding the cast-iron piece in the chair f.

g g are the ends of a rod of round iron, which is used as a substitute for a tie, turned square at each end, and sharpened and laid across from the chair of one rail to the other, and driven like a spike through a hole in the chair into the ground.

This will hold the chair and the rail in position until supported and made firm by the paving being laid under and into the rail and its supporting cast-iron flange.

h h are openings left in the cast-iron piece, through which parts of the paving-stones may pass, in order to hold the rail down, and make it a part of and incorporate it with the paving.

When the paving-stones are pitched or leaned in their position, the holes are made correspondingly pitching, or inclined, so as to receive a part of the paving, or some of the courses of the blocks.

The design in this arrangement is to make the supporting part of the rail broad enough to reach to the depth of the paving, there held in a chair beneath the stones, and the support resting on a series of flat stones laid along the line of the rails, the ends of the paving-stones lying upon this course, and under the edge of the rail.

In this way the paving will be kept from sinking down along the side of the rail, and be enabled to dispense with stringers, sleepers, and ties.

I claim as original and new, for which I desire protection and a patent—

The formation of a wrought-iron flange of the rail, or a cast-iron attachment to the under part of it, with openings square or inclined, as the case may require, into which, or through which to pass the paving-stone for the support of the rail, and so designed as to furnish a substitute for wooden stringers and ties.

ZEBINA EASTMAN.
